UNITED STATES PATENT OFFICE.

GEORGE R. H. LEFFLER, OF BALTIMORE, MARYLAND.

IMPROVEMENT IN DISTILLING TURPENTINE FROM WOOD.

Specification forming part of Letters Patent No. 41,435, dated September 27, 1864.

To all whom it may concern:

Be it known that I, GEORGE R. H. LEFFLER, of the city and county of Baltimore, in the State of Maryland, have invented a new and Improved Process for Distilling Turpentine; and I do hereby declare the following to be a full and exact description of the same.

This invention consists in distilling turpentine directly from yellow pine or other wood in the form of blocks, shavings, sawdust, or any chips made by machinery or otherwise and immersed or thoroughly saturated with water or steam, whereby the turpentine contained therein may be thoroughly extracted without danger of combustion, and by which a considerable quantity of this useful article may be obtained from wood which has been depleted as far as possible by the process most commonly employed.

In order that others skilled in the art to which my invention appertains may be enabled to fully understand and use the same, I will proceed to describe the manner of carrying it into effect.

The blocks, chips, shavings, or sawdust are either steamed or placed within the still with a large quantity of water and then thoroughly boiled. This boiling or steaming process ex-

tracts from the wood the greater part of the juicy matter containing turpentine and adapts any that may remain in the woody substance itself after it has undergone the boiling or steaming operation to be more readily distilled. After the juicy matter containing the turpentine has been released from the wood by the boiling or steaming process the turpentine may be distilled therefrom in customary manner, a large quantity of water being, by preference, used in the still.

By this process the distiller is enabled to produce a considerable quantity of turpentine from wood which has already been depleted as completely as possible by the usual process, and which may have been thrown aside as altogether useless for the purpose in question.

Having thus described my invention, what I claim as new therein, and desire secure by Letters Patent, is—

Distilling turpentine directly from wood saturated or thoroughly moistened with steam or water, substantially as set forth.

G. R. H. LEFFLER.
